METHOD AND APPARATUS FOR FORMING TRIANGULAR POSTS

Albert Paul Theobald, St. Paul, Minn., assignor to Waldorf Paper Products Company, Wabash, Minn., a corporation of Minnesota

Application July 25, 1957, Serial No. 674,253

19 Claims. (Cl. 93—84)

This invention relates to an improvement in triangular post forming machines and deals particularly with a method and apparatus forming triangular corner posts useful in the reinforcing of shipping cases and the like.

The shipment of heavy appliances in paper board containers has increased considerably during recent years. In many instances the appliance such as a washing machine, dryer, or other such bulky and heavy object is bolted or otherwise secured to a wooden base frame and the appliance is enclosed within a heavy case of corrugated board or the like. In order to prevent injury to the appliance during the storage and shipment, and to permit the stacking of one such appliance upon the other without resulting damage, triangular corner posts made of heavy corrugated board are being used. One such post is inserted in each corner of the shipping container and acts to hold the shipping container in properly spaced relation from the appliance. These corner posts are extremely strong and resistant to vertical compression and as a result the shipping cases may be piled one upon the other without damage to the appliances.

Formerly these posts had been produced by a hand operation. Usually the corner posts are made of four hingedly connected panels, two of which are overlapped and adhered or otherwise fastened together. In view of the fact that posts of this type cannot be nested together, they require considerable space to store and are likewise uneconomical to ship. Thus it is usually most practical to form the posts from flat sheets of corrugated board at the point of shipment of the appliances. The cost of producing these posts manually is high and as a result the posts would normally add very materially to the cost of the container. It is an object of the present invention to produce a method and apparatus forming these posts, the apparatus taking the flat sheets, folding them into proper form and adhering them together.

An object of the present invention resides in the provision of an apparatus which acts to plunge a flat sheet of corrugated board or the like into a suitable pocket in a manner to prebreak all of the fold lines along which the board is creased. The edge panels of the series are next folded into overlapping relation and adhered in this position. The triangular post then passes through a compression unit which acts to hold the overlapped panels in surface contact during the drawing of the adhesive. As a final step of the series, the overlapped panels which form the diagonal panels of the corner post are creased or kinked inwardly so as to lend flexibility to this inner diagonal wall of the post structure.

A feature of the present invention resides in the provision of an apparatus which operates automatically in cycles to form a complete post during each cycle. When the machine is operated, a feed mechanism moves a flat blank from storage position to position to be formed over the forming pocket. A plunger next forces the sheet down into the forming pocket prebreaking all of the scores of the sheet. A laterally extending folding mem-

2

ber next moves against the prebroken sheet and folds one of the panels to be overlapped into horizontal position. As the next cycle of operation begins, and as the next sheet is fed into position over the forming pocket, 5 the remaining panel to be overlapped is folded down into surface contact with the first folded of these overlapping panels and the two are adhered together. As the corner post moves from beneath the forming plunger, it acts to advance the corner posts which have been previously formed through the compression unit. As each corner post arrives at a final position in the compression unit, the two overlapped panels are longitudinally creased or folded together to give the double thickness wall flexibility.

These and other objects and novel features of the present invention will be more clearly and fully set forth in the following specification and claims.

In the drawings forming a part of the description—

20 Figure 1 is a perspective view of a post forming machine showing the general arrangement of parts therein.

Figure 2 is a cross-sectional view looking toward the feet end of the apparatus, the position of the section being indicated by the line 2—2 of Figure 1.

25 Figure 3 is a sectional view showing a detail of the gluing mechanism.

Figure 4 is a sectional detail showing the connection between the main operating plunger and the feed plate.

30 Figure 5 is an end elevational view of the detail construction illustrated in Figure 4.

Figure 6 is a sectional view through the glue applicating cylinder illustrated in Figure 3.

35 Figure 7 is a horizontal sectional view of the post folding mechanism, the position of the section being indicated by the line 7—7 of Figure 6.

Figure 8 is a perspective view of a portion of the folding mechanism shown in Figures 6 and 7.

40 Figure 9 is a sectional view through an end portion of the mechanism showing the manner in which the formed posts are creased.

Figures 10, 11, 12, 13, 14, and 15 are diagrammatic sectional views through the apparatus showing various stages of the forming operation.

45 Figure 16 is a diagrammatic view of the blank from which the posts are formed.

Figure 17 is an end view of the post sheet at the start of the forming operation.

50 Figure 18 is a sectional view through the packing case at the top of the corner posts, the position of the section being indicated by the line 18—18 of Figure 19.

Figure 19 is a sectional view vertically through the packing case outwardly of the corner posts, the position of the section being indicated by the line 19—19 of Figure 18.

55 The corner posts are indicated in general by the letter "A" and are formed of the blank best illustrated in Figure 16 of the drawings. The corner posts are formed of a generally rectangular sheet and are folded along three parallel fold lines 10, 11, and 12 to form an end panel 13, a pair of intermediate panels 14 and 15, and end panel 16. The end panels 13 and 16 include a central fold line, the panel 13 being divided by a central

60 fold line 17 and the panel 16 being divided by a central fold line 19. The central fold lines 17 and 19 are designed to provide flexibility of the diagonal wall of the post as will be later described.

65 Figures 18 and 19 indicate a typical use for the corner posts A.

70 These figures show a generally rectangular container having spaced parallel side walls 20 and 21 and spaced

parallel front and rear walls 22 and 23, the various walls being rectangularly connected into tubular relation.

The container, which is indicated in general by the letter "B" is designed to contain an appliance such as an electric gas dryer C. The walls of this dryer are spaced from the corresponding walls of the outer container and the dryer is mounted upon a generally rectangular wooden platform indicated in general by the numeral 24. A corner post A is provided at each vertical corner of the container with the single thickness panels 14 and 15 in surface contact with the adjoining vertical panels of the container and with the overlapped panels 13 and 16 extending diagonally across the corners of the container. These panels 13 and 16 are bent inwardly somewhat as indicated in Figure 18 of the drawings so as to provide a cushioning effect and to hold the walls of the container in space relation from the surface of the dryer C. As is indicated in Figure 19 of the drawing the bottom of the container is closed by closing flaps 25 which extend beneath the platform 24 while the top of the container is closed by closing flaps 26.

It will be seen that because of the resistance to compression of the corner posts, the containers are extremely strong and may be packed one upon the other to a considerable height in spite of the weight of the dryers contained.

Figure 1 of the drawings shows the general assembly of the apparatus, a portion of the compression unit being broken away so that the overall size of the apparatus may be shown on a larger scale. The forming end of the apparatus is shown as including a frame which is indicated in general by the numeral 27 and which is supported by suitable leg units such as 29, 30 and 31. The frame 27 includes as a part a table surface 32 which is elongated longitudinally of the apparatus and which is longitudinally slotted as indicated at 33 at least throughout the feed end portion of the apparatus. The center portion of the table is reinforced by longitudinally extending panels 34 shown in Figures 1 and 5.

A hopper 35 is supported to extend upwardly from the table top 32 at the feed end of the apparatus. The hopper 35 may include a rear wall 36 which extends along one side of the apparatus, and side walls 37 and 39 which extend along the forward and rear sides of the feed portion to contain a series of blanks A in superimposed relation. As indicated in Figures 2 and 3 of the drawings, the forward wall 37 terminates slightly above table top 32 to provide a slot 40 through which the lowermost blank A may move.

The apparatus includes a feed plate for moving the lowermost blank A from the superimposed position in the hopper 35 to an advanced position for forming. This feed plate is indicated in Figures 1, 4 and 5 of the drawings and is designated by the numeral 41. The plate 41 includes a thin forwardly projecting portion 42 which at all times remains beneath at least an edge of the carton blanks A when the feed plate 41 is in full retracted position which would be slightly to the right of the position indicated in Figure 4. The plate 41 is provided with a tapered rear edge 43 so the plate can slide freely beneath superimposed blanks. Above the level of the thin forward portion 42 is provided a series of forwardly extending fingers 44 which project forwardly and engage the lowermost blank A to move this lowermost blank into post forming position upon reciprocation of the plate 41.

An operating cylinder 45 shown in Figures 1 and 2 of the drawing is mounted on a suitable super structure 46 beneath the feed table and a piston within the cylinder 45 is connected to an elongated piston rod 47 extending beneath the table 32 and below the central slot 33 therein. A vertical web 49 is provided with a longitudinal bearing 50 at its lower edge to accommodate the rear end of the piston rod 47. The upper end of the web

49 is connected to the under surface of the feed plate 41, the web extending through the slot 33. Thus reciprocation of the piston within the cylinder 45 acts to reciprocate the feed plate 41 to move a carton blank from the bottom of the superimposed blank to a forming position.

As is evident from Figures 4 and 5 of the drawings a sleeve 51 is provided on either side of the web 49 having eccentric pivots 52 on the ends thereof. Rollers 53 are supported on the eccentric pivots 52. A bolt 54 extends axially through one sleeve 51 and through the eccentric thereon, extends through the web 49 and is threaded axially into the other sleeve 51. By loosening the bolt 54, either or both sleeves may be rotated to adjust the relation of the rollers 53 against the under surface of the reinforcing channels 34 to hold the feed plate in surface contact with the table 32. Stated otherwise, the guide plate 41 and the rollers 53 cooperate to prevent vertical movement of the web 49 during its travel.

An opening 55 is provided in the table 32 formerly of the hopper 35, a portion of this opening being broken away in Figure 1 to disclose the lower mechanism. As is indicated in Figures 2, 10, and 11 of the drawing, one side of the pocket includes a downwardly inclined lip 56 terminating in a vertically extending lower edge flange 57. The other side of the pocket 55 also includes a downwardly and inwardly inclined flange 59 and a downwardly extending vertical panel 60 which is somewhat longer than the marginal edge 57. The panel 60 is provided on its inner surface with a horizontally extending bar 61, the lower edge of which forms a shoulder for a purpose which will be later described more in detail. The pocket 55 is slightly longer than the blank A so that the entire blank may be plunged down into this pocket in a manner which will be more completely described.

An upright 62 extends upwardly from the frame 27 and a box-like support 63 is mounted on the upright 62 to extend transversely to the longitudinal axis of the machine. The support 63 supports a vertical mounting panel 64 to which is secured a vertical cylinder 65. The cylinder 65 acts as a slidable support for a piston to which is attached a piston rod 66 which is vertically reciprocable. A tubular sleeve 67 is attached to the piston rod 66 to reciprocate vertically therewith. A bracket 69 is provided at the lower end of the sleeve 70, the bracket 69 being connected along opposite parallel hinges to a pair of plates 71 which are connected in V-shape relation. A second pair of plates 72 and 73 are arranged in V-shape relation, but are at a greater angle apart than the plates 70 and 71. The apex or juncture between the V-shape plates 70 and 71 is hinged connected at 74 to the apex between the plates 72 and 73. Thus one pair of V-shape plates can hinge relative to the other.

A pair of braces 75 extend between the sleeve 67 and the interior of the connected V-shaped plates 70 and 71 to form a brace for the construction and to hold the plates with their apex in a horizontal plane. While describing the feed table and various other elements as being on a horizontal plane, it should be understood that in actual practice the entire machine may incline upwardly to some extent so that the hopper 35 is at the lower end of the machine and the finished posts are ejected from the higher end thereof for the purpose of convenience.

The purpose of the arrangement just described is to fold the blank A from a flat condition into the form illustrated in Figure 10 of the drawings. The apparatus includes a sub table 76 forming a part of frame 27 and onto which the blanks are plunged. A bracket 77 rests upon the sub table 76 and supports a guide plate 79 at an acute angle to the table 76 beneath the center portion of the pocket 55. As the plunger 66 moves downwardly, the hinge line or apex 74 of the lowermost connected plates 72 and 73 is moved against the blank along the central line of fold 11 of the blank. Continued down-

ward movement of the plunger causes the two plates 72 and 73 to engage with equal force against the panels 14 and 15 on opposite sides of the central fold line 11, both plates assuming a substantially equal angle to the horizontal. As the blank is of substantially equal width on opposite sides of the central fold line 11, the blank is bent along this line and urged downwardly into the pocket, the vertical edges 57 and 60 of the opposite sides of the pocket tending to fold the blank along the fold lines 10 and 12 so that the longitudinal edges of the blank including the panels 13 and 16 extend in substantially vertical relation. This plunging action continues until the panel 14 underlying the plate 72 engages against the inclined panel 79 on the sub frame 76. Further downward action of the plunger causes the combined plates 72 and 73 to hinge along the hinge axis 74 until the plate 72 engages against the plate 70. At this point, the plate 73 is in horizontal position and acts to fold the panel 15 into horizontal position. At this point of the procedure, the marginal edge of the panel 16 engages beneath the bar 61 as is indicated in Figure 10 of the drawings, thus folding the blank in the form illustrated in this figure. The plunger may then be reciprocated upwardly, leaving the partially folded blank in the arrangement shown in Figure 10 at the bottom of the pocket 55.

As indicated in Figures 2 and 7 of the drawings, a supporting plate 80 extends laterally from the frame 27 and is supported in a generally horizontal position by a supporting brace 81. The plate 80 acts to support a transversely extending cylinder 82 including a piston connected to a piston rod 82. A plate 84 is supported for transverse slidable movement beneath the sub-table A lug 86 is provided on the under surface of the slidable plate 84 through which the piston 83 extends, and the piston rod is connected to this lug by nuts 87 or other suitable means. As is indicated in Figure 1, the sub table 76 is notched as indicated at 89 and an angle bracket 90 is connected to the extremity of the slidable plate 84 and extends through the notch 89. The angle bracket 90 supports a pair of plates 91 and 92 which are arranged in V-shape relation. The plate 92 is angled upwardly from the sub table 76 in opposed relation to the angle of the plate 79 while the plate 91 extends in a substantially horizontal plane. As is indicated in Figure 8 of the drawings the plate 73 is notched at regular intervals as indicated at 93 so that the plate 73 is in effect a series of figures. The lower edge of the plate 92 is similarly notched to provide spaced fingers 94. The fingers 94 at the lower edge of the plate 92 extend between the fingers forming the plate 73 or into the notches 93 so that the lower edge of the fingers 94 may interfere with the plate 73 when the angle 90 bearing the plates 91 and 92 is moved laterally.

As a next step of the operation of the apparatus, the piston within the cylinder 82 is actuated to move the plate 84 to the left as viewed in Figures 2, 10, and 11. The figures 94 extend beneath the blank A at the juncture between the panels 15 and 16 or along the fold line 12 so as to tilt the panel 15 upwardly. The movement of the angle bracket at 90 to the left from the position shown in Figure 10 also brings the plate 91 against the panel 16 and folds this panel 16 into the horizontal position. Thus when the bracket 90 is in the position shown in Figure 11 of the drawings, the panels 14 and 15 of the blank A are in V-shape relation and are approximately 90 degrees apart while the panel 16 is in horizontal position forming a triangular structure. At this point, the panel 13 of the blank is still in vertical position as shown in Figure 11.

Referring back at this point to the feeding movement of the carton blank from its position within the hopper 35 to its position above the pocket 55 adhesive is applied to a portion of the upper surface of the panel 13. This is accomplished by a glue mechanism indicated in general by the numeral 95 and shown mounted upon

the hopper wall 37 in Figure 2 of the drawings. This structure is shown somewhat more in detail in Figures 3 and 6 of the drawing. Obviously other means of applying the adhesive may be employed, but the one specifically illustrated in the drawings has certain advantages which will become apparent upon the description of this apparatus.

A hinge plate 96 is mounted upon the hopper wall 37 and is provided with horizontally aligned bearings 97 along its lower edge. A second hinge plate 99 is hingedly connected to the hinge plate 96 by the hinge pin 100. The hinge plate 99 supports an angle bracket 101 which in turn supports a transversely extending cylindrical sleeve 102. As is indicated in Figure 6 of the drawings, the sleeve 102 is slotted in its lower extremity at 103, and preferably the sleeve includes a series of slightly spaced longitudinally aligned slots although a single slot could also be employed. An upwardly extending pin 103 is provided upon the hinge plate 99 and this pin is freely slidably in a sleeve 104. A spring 105 connects the upper end of the sleeve 104 to the fixed hinge plate 96 and this spring 105 normally tends to pull the upper end of the sleeve 104 toward the hopper wall 37 to hold the sleeve 102 slightly elevated above the table 32.

A lever arm 106 is hingedly connected at 107 to a fixed portion of the frame such as to the upright 62 and a fluid cylinder 109 is hingedly connected at 110 to the hopper wall 37 and includes a piston connected to the piston rod 111 which bears against an intermediate part of the lever arm 106. Once fluid under pressure is introduced into the cylinder 109 the piston rod 111 is moved to the left as viewed in Figure 3 thus acting to swing the lever arm 106 about its pivot 107 in a clockwise direction.

A spring 112 connects the lower end of the lever arm 106 to the upper end of the sleeve 104 opposite its connection with the spring 105. When the piston within the cylinder 109 is in its normal position, to which it is biased by the spring 113, the spring 112 is relaxed and permits the spring 105 to raise the cylinder 102 above the level of the table 32. However when fluid under pressure is introduced into the cylinder 109, swinging the lever arm 106 in a clockwise direction, the spring 112 is elongated and placed under sufficient tension to swing the cylinder 102 against the surface of a blank A which is at that time traveling beneath the cylinder.

As is indicated in Figure 2 of the drawings, one end of the cylinder 102 is connected to an adhesive reservoir 114 by a flexible conduit 115. A valve 116 is provided in this conduit and the adhesive in the reservoir 114 is under pressure. Thus when the valve 116 is open, adhesive under pressure is forced into the cylinder 102 and through the slots 103 for application to the blank A. The slots 103 in the cylinder 102 are properly proportioned relative to the viscosity of the adhesive used so that when the pressure is withdrawn, no adhesive will flow through the slots. Stated otherwise, the adhesive must be forced from the cylinder by pressure which is only applied during the movement of the blank A beneath the cylinder 102. Simultaneously with the opening of the valve 116, pressure is also applied to the cylinder 109 so as to hold the glue cylinder 102 in surface contact with the blank A during application of the adhesive.

Thus it will be apparent that as the blank A moves from storage position in the hopper 36 to position over the pocket 55, adhesive is applied to the upper surface of the panel 13. When the blank A is forced into the pocket 55 by the plunger structure which may be designated in general by the numeral 117, the adhesively coated surface is on the right side of the panel 13 as it is viewed in the Figure 10. Thus the adhesive surface will contact the panel 16 when the blank is in completely folded condition.

The structure for initiating the folding of the panel

13 is best indicated in Figures 7 and 12 of the drawings. As shown in the former figure, a pivot 119 is supported by a bracket 120 mounted upon a fixed upright portion 121 of the framework. A sleeve 122 pivotally supported upon the pivot 119 and an angularly extending folding arm 123 is supported by the sleeve 122 to pivot in unison therewith. The arm 123 is provided with an end portion 124 which projects beyond the sleeve 122. A cam pin 125 is mounted upon the plate 84 and projects through a slot 126 in the subtable 76 which may be seen in Figure 7 of the drawings. This cam pin 125 engages the end 124 of the folding arm 123 and swings this folding arm in a counter clockwise direction about its pivot 119 as the plate 84 nears the extremity of its stroke and after the panel 16 has been folded down into horizontal position by the plate 91. As a result of this movement, the panel 13 is folded down to overlie the plate 91. However, the arm 123 is so bent that the adhesively coated undersurface of the panel 13 does not contact the plate 91.

This completes a cycle of operation. However, before the plate 84 is projected into its open position, the next feeding operation starts. A plunger 129 which is shown in Figures 1 and 4 of the drawings is anchored to the web 49 which connects the feeder plate of 41 to the piston rod 47 connected to the piston in the feeder cylinder 45. Thus the plunger arm 129 operates in unison with the feeder plate. A pressure plate 130 is supported at the end of the plunger 129, the plunger 129 and plate 130 acting to force the folded posts into the compression portion of the apparatus. As indicated in Figure 1 and Figure 7 of the drawings the upper plate 91 forming a part of the lateral folding mechanism is notched as indicated at 131 to permit the pressure plate 130 to start urging the folded post beneath a folding horn 132 illustrated in Figures 1 and 7 of the drawings to complete the folding operation. The pressure plate 130 moves the folded blank A sufficiently to engage the forward end of the post beneath the folding horn 132. At this stage of the operation, fluid is introduced into the cylinder 82 to urge the plate 84 to the right as indicated in Figure 2 of the drawings, thus withdrawing the inclined plates 91 and 92 from engagement with the carton blank and simultaneously releasing the cam pin 125 from its engagement with the end 124 of the folding arm 123 and permitting the spring 133 to return this folding horn to its normal retracted position.

As the forward end of the blank A engages beneath the folding horn 132, and forward movement of the plunger 129 and its pressure plate 130 continues, the panel 13 is urged against the panel 16 and adhered thereto with the adhesive which has already been applied to the undersurface of the panel 13. The compression unit is indicated in general by the numeral 134. In general, this compression unit includes a pair of plates 135 and 136 which are arranged in a V-shape relation and secured at their lower extremity 137 to a suitable support such as 139. The upper edges of the inclined plates 135 and 136 are provided with right angularly extending flanges 140 and 141 respectively. These flanges 140 and 141 act to support spaced pivots 142 and 143 respectively which support rollers 144 and 145. These rollers engage the panels 14 and 15 near their point of connection with the panels 13 and 16 respectively and assist in reducing the force required to push the posts through the compression unit.

The compression member also includes an upper frame member 146 which supports spaced hangers 147 which in turn support an angle iron 149 just above the level of the upper surface of the folded blank A. The angle 149 includes a vertical flange which supports spaced pivots 150 which support spaced rollers 151. Thus the top of the post is also held in proper position during movement of the post through the compression unit. The rollers 151 combine with the rollers 144 and 145 to hold the post in proper form during the drying of the adhesive.

With reference now to Figure 14 of the drawings, and with further reference to Figures 1 and 9, it will be noted that a framework is supported by the frame legs 31 including a table 152 and a pair of spaced vertical channels 153 and 154 connected by cross connecting channels 155. At the entrance end of this framework, a downwardly projecting bracket 156 is provided which supports a transverse pivot 157 which acts as a pivot axis for a creasing wheel 159. The creasing wheel 159 is located beyond the end of the rollers previously described and at this point of the operation, the folded blank is supported by an inclined plate 160 which may be the end of the plate 136 and by an angularly inclined flange 161 which may provide a narrowed extension of the plate 135. An angle bracket 162 is supported inwardly of the channel 153 by spacing members 163. An angle plate 164 rests upon the table 152 or is supported slightly above this table and the vertical flange 165 of this angle 164 supports an angular guide 166 through the medium of spacers 167. The plate 160 with its flange 161, combined with the angular guides 162 and 166 guide the post in its movement as the creasing wheel 159 engages the central portions of the adhered panels 13 and 16, folding these panels inwardly along their central fold lines 17 and 19.

As is indicated in Figure 9 of the drawings, the table 152 also supports a third vertical channel member 169 which is also connected to the channels 153 and 154 by the transverse channels 155. The channels 169 act as a support for a transverse cylinder 170 which includes a piston connected to the connecting rod 171. The end of the piston rod or connecting rod 171 is connected to the vertical flange 172 of a channel 173. The other vertical side 174 of the channel 173 is connected to a plurality of pushing rods 175 which are connected to the angle bracket 164. A spring 176 connects the channel flange 174 to the channel 169 to retract the plunger 171 when the pressure is not experienced in this cylinder.

When fluid is introduced into the cylinder 70, the plunger 171 slides the channel 173 to the right acting through the push rods 175 to force the angle members 164 to the right as viewed in Figure 9. This causes the blank A to be kinked inwardly in the manner illustrated in the drawings to form a definite break in the double panels which will form the diagonal panels extending across the corners of the case. Figure 9 of the drawings shows the blank A in bent form. The panels 13 and 16 always fold inwardly due to the fact that they have been broken inwardly to some extent by the creasing roller 159. After the blank has been bent into the form shown in Figure 9, the pressure in the cylinder 170 is released and the springs 177 return the angle member 164 to its normal retracted position shown in Figure 14 of the drawings. Due to the resilience of the material forming the post, the posts will partially return to their normal position and will remain in approximately the cross-sectional shape illustrated in Figure 14 of the drawings.

The operation of the apparatus has, for the most part, been described in conjunction with the description of the device. As a short summary of the operation, the cycle began with the feed plate 41 and plunger 129 in the retracted position illustrated in Figure 1, with the plunger mechanism 117 in elevated position, and with the laterally operating folding plates 91 and 92 in post forming position as shown in Figure 11 of the drawing, and with the folding horn 123 also in post forming position shown in Figure 12. Fluid under pressure is applied to the plunger cylinder 45 tending to retract the piston in this cylinder and to move the plunger 129 and feed plate 41 to the left from the position shown in Figure 1. The feed plate picks up the lowermost blank A of the stack of the blanks within the hopper 35 and the pressure plate 130 of the plunger 129 enters the V-shaped space formed by the fixed plate 14 and the moveable plate 92, the pressure plate 130 entering the notch 31 at the end of the

top folding plate 91. This motion continues until the blank A is fed into position above the forming pocket 55 and any post in the forming pocket is formed into the compression unit. However, during this operation, fluid is applied to the cylinder 82 to force the folding plates 91 and 92 out of the path of the pressure plate 130.

As the blank is fed into place, the forward edge of the blank passes beneath the glue applicator cylinder 102 which is in slightly raised position above the table 32. Just at the time the forward edge of the blank passes beneath the glue cylinder 102, pressure is applied to the cylinder 109 applying tension to the spring 112 and swinging the glue cylinder 102 against the upper surface of the blank. Simultaneously, pressure is applied to the valve 116 to open this valve and to transmit pressure to the glue cylinder 102 to force adhesive from this cylinder. Thus during travel of the blank beneath the glue cylinder, glue is applied to a portion of the upper surface of the panel 13.

When the feed plate 41 and plunger 129 reach fully retracted position or the limit of movement of the piston within the cylinder 45 fluid is automatically applied to the opposite end of the cylinder 45 tending to project the piston rod 47 and to return the feed plate 41 and plunger 129 to their starting position. When this movement is accomplished, fluid is automatically applied to the cylinder 65 to lower the plunger element 117 against the blank and to force the blank into the pocket 55.

As the plunger assembly 117 moves downwardly, the hinge plates 72 and 73 engage the approximate center of the blank A or along the fold line 11 which tends to fold the blank centrally into sections. During this operation, the plate 73 swings upwardly so that equal pressure is applied to both sides of the blank. This folding operation continues until the panel 14 of the blank engages the inclined fixed plate 79 and limits the lowering of the portion of this panel. As a result, the plate 72 swings toward the fixed plunger plate 70 and the plate 73 swings toward horizontal position to move the blank into position illustrated in Figure 10. In this position the panel 14 is inclined to the angle of the fixed plate 79, the adjoining panel 13 is in substantially vertical position against the pocket flange 57, the panel 15 is horizontal against the bottom of the pocket, and the panel 16 extends vertically with its upper edge beneath the shoulder 61 on the pocket side 60.

The plunger assembly 117 then is returned to elevated position by fluid operation of the cylinder 114 and fluid under pressure is applied to the cylinder 82 tending to retract the piston in this cylinder and to move the plate 84 to the left from the position shown in Figure 10 of the drawings to the position shown in Figure 11 thereof. Obviously, spring means may be employed to produce this return movement in place of the fluid movement which has been described. As the plate 91 strikes the panel 16, it folds this panel toward a horizontal position. Subsequently, the plate 92 engages the juncture 12 between the panels 15 and 16 to swing the panel 15 into upwardly inclined position against the upper surface of the plate 92. Just before the completion of the movement of the plate 84, the cam pin 125 strikes the end 124 of the folding arm 123 and swings this arm in a counter clockwise direction as viewed in Figure 7 thus folding the panel 13 down into position to partially overlie the folding plate 91 but spaced sufficiently therefrom so that the adhesively coated undersurface does not engage the plate 91.

This completes the cycle. During the next cycle of operation, the post which has been formed is engaged by the pressure plate 130 of the plunger 129 moving the post beneath the folding horn 132 while the post is held in partially folded position as described. The folding plates 91, 92 are then returned to the disengage posi-

tion shown in Figure 10 permitting the pressure plate 130 to force the post into the compression unit.

As each post is forced into the compression unit, its forward edge engages the rear edge of the next or previously formed post and urges it toward the outlet end of the compression unit. The last post of the series is advanced beneath the creasing wheel 159 to its final position at the outlet end of the machine. During the dwell of the cycle the cylinder 170 is actuated to kink the post inwardly as shown in Figures 9 and 15. The completely formed post is forced from the outlet end of the machine by the entrance of the next post into its final position.

In accordance with the patent statutes I have described the principles of construction and operation of my post-forming machine, and while I have endeavored to set forth the best embodiment thereof, I desire to have it understood that obvious changes may be made within the scope of the following claims without departing from the spirit of my invention.

I claim:

1. A post forming apparatus for forming a generally triangular post from a flat blank having four panels hingedly secured together along substantially parallel fold lines, the apparatus including a plunger means engageable with the blank for folding the blank along its intermediate fold line into U-shaped form with the end panels of the blank generally parallel, plunger means engaging one of said parallel end panels of the blank folding said one end panel of the series to extend diagonally across the next adjoining panels and folding said next adjoining panels into angular relation, means folding the other end panel of the series to overlie the first folded end panel, and means securing the two end panels of the series in surface contact.

2. The apparatus described in claim 1 and including means applying adhesive to one end panel of the series prior to folding this end panel into surface contact with the other end panel.

3. The apparatus of claim 2 and including means moving the folded blank longitudinally and holding said end panels in surface contact.

4. A post forming apparatus for forming a generally triangular post from a generally rectangular blank creased along parallel fold lines to form four hingedly connected panels, the apparatus including a frame including a forming pocket, means positioning a blank in registry with said pocket, plunger means engageable with the blank to fold the same along its central fold line into said pocket, plunger means engageable with an end panel of the blank in said pocket to fold the end panel to extend diagonally across the two adjacent panels, and means engageable with the remaining end panel of the series to fold the remaining end panel into surface contact with the first folded end panel, and means securing said end panels in surface contact.

5. The structure of claim 4 and including means moving said post longitudinally from said pocket and means engageable with said superposed end panels to fold the same inwardly between their side edges.

6. The structure of claim 5 and in which said last named means engages said superposed panels upon longitudinal movement of the post.

7. A post forming machine for forming generally triangular posts from substantially rectangular flat blanks creased on substantially parallel fold lines to provide four hingedly connected panels, said apparatus including a feed table having a forming pocket therein, means engageable with a blank on said table to move the same from a starting position to position over said pocket, means engageable with a blank positioned over said pocket to fold the blank along its intermediate crease and plunge the blank into said pocket, means engageable with an end panel of the series to fold the same to extend diagonally across the next two adjoining angularly related panels, means engageable with the remaining end panel of the series to

fold the same to overlie said first folded end panel, and means moving said blank longitudinally of its score lines from said pocket while holding said end panels superposed.

8. The structure of claim 7 and including means for applying adhesive to one of said end panels during movement of the blank from starting position to position over said pocket.

9. The structure described in claim 7 and in which said means for moving said blank from starting position is connected to said means for moving said blank from said pocket for operation in unison.

10. The structure described in claim 7 and in which the means for moving the blank from starting position and the means for moving the blank from said pocket comprise connected reciprocable plungers.

11. The structure of claim 7 and including means engageable with said superposed end panels for folding the same inwardly intermediate their longitudinal edges.

12. The structure of claim 7 and including means engageable with said superposed end panels during movement of said blank for folding the same inwardly, and means engageable with opposite edges of said superposed end panels for further folding the same inwardly.

13. A blank folding apparatus for folding a flat rectangular blank creased along parallel fold lines to form four connected panels into a generally triangular post, the apparatus including a forming pocket, means engaging the blank along its intermediate crease to fold the blank into V-shape into said pocket, means engageable with one intermediate panel of the series to hold the same upwardly inclined from the center crease, means forming one side of said pocket holding the one end panel connected to said one intermediate panel in substantially vertical relation, means folding the other intermediate panel into substantially horizontal position, means forming an opposite side of said pocket holding the remaining end panel in substantially vertical position, means engageable with said other intermediate panel to fold the same into upwardly inclined position from the center crease and folding said remaining end panel into substantially horizontal position to extend diagonal of said intermediate panels and means engageable with said one

end panel to fold it into overlying relation to said remaining end panel.

14. The structure of claim 13 and including means engageable with the longitudinal edge of said remaining end panel for holding the blank in said pocket while said means engaging the blank along its intermediate crease is withdrawn, and means for withdrawing said last named means.

15. The structure of claim 13 and in which the means engaging the blank along its intermediate crease includes a plunger having an elongated blank engaging member of V-shaped section hingedly connected thereto substantially along its apex.

16. The structure of claim 15 and in which said means engageable with one intermediate panel acts through the blank to hinge said blank engaging member.

17. A method of forming a corner post from a generally rectangular blank divided by three parallel creases into four connected panels, the method comprising the steps of folding the blank along its intermediate crease into V-shape, folding the blank along its outer creases to hinge the end panels relative to the intermediate panels, folding one intermediate panel into a substantially horizontal plane while holding the other intermediate panel upwardly inclined from the intermediate crease and holding the end panels substantially vertical, folding the end panel connected to the horizontal panel inwardly toward horizontal position while simultaneously folding the horizontal panel upwardly into inclined relation with the horizontal, and folding the remaining end panel to overlie the first folded end panel.

18. The method of claim 17 and including the step of applying adhesive upon one of said end panels prior to the folding operation.

19. The method of claim 17 and including the further step of moving the folded blank longitudinally of its creases and urging said end panels into surface contact during this movement.
